TRAVELING BLOCK LIMIT CONTROL

Clarence W. Halderman, Ojai, Calif.

Application February 14, 1948, Serial No. 8,487

14 Claims. (Cl. 254—173)

1

This invention relates generally to improved control or signaling mechanism for use with hoisting apparatus of an oil well.

Serious accidents often occur during the drilling of an oil well because of the improper operation or handling of various equipment. One type of accident of frequent occurrence results during the hoisting of a tool or other object when the draw works operator fails to halt the upward movement of the traveling block at the proper time. The unintended traveling block continues its upward movement to impact against the crown block with a powered jolt, which may part the cable or cause other mechanical failure and permit the equipment being lifted to fall, thus endangering workmen in the vicinity.

This invention is designed to prevent accidents caused by such overtraveling of the hoisting mechanism by providing a safety device to either automatically stop rotation of the winding drum, or to signal the operator when the traveling block has reached its highest operative position. To effect such automatic operation, the device includes novel mechanism by which it is rendered responsive to the winding of a predetermined critical turn on the hoisting drum. In its preferred form, the instant invention also makes provision for simple adjustment of the safety device to permit varying of the turn to which it will react. Such adjusting means may comprise two independent adjustments, one governing the layer of winding to which the device will react, and the other determining the particular effective turn in that layer.

A second object of the present invention is to provide means which will automatically stop the hoisting process or signal the operator in case the cable does not spool properly on the winding drum. This is preferably effected by the same mechanism as is used in controlling the upward travel of the block.

It is a further object of the invention to provide a control device of the above type in which the control mechanism is positioned beneath the drum to occupy otherwise unused space and attain the other obvious advantages of such a protected location.

In the preferred form, the present invention comprises a winding drum, a bar extending substantially parallel to the axis of the drum at a position located outwardly from the drum, and control means responsive to outward deflection of the bar to a predetermined operative position. The bar is outwardly deflectible to the defined position in response to the winding of a predetermined critical turn on the drum.

2
terminated critical turn, so that the control means will be automatically actuated as the hoisting process reaches the point at which that turn is wound onto the drum. To cause the bar to react in the above manner, it may be provided with an inwardly facing projection or lug which the cable will contact after being wound on the drum to the critical point, such engagement acting to move the bar outwardly to the operative position. This lug or projection may comprise a plurality of removable sections or blocks, and the position of each section may be variable longitudinally of the bar to permit setting of the bar for reaction to a desired turn. By proper design of the blocks, the bar may be rendered deflectible also in response to fouling of the cable.

The above and further features and objects of the present invention will be better understood from the following detailed description of a typical embodiment, as illustrated by the accompanying drawings, in which:

Fig. 1 is a vertical central section through the drum and associated safety mechanism, taken on line 1—1 of Fig. 2;

Fig. 2 is an enlarged side elevation taken on line 2—2 of Fig. 1;

Fig. 3 is a fragmentary elevation taken on line 3—3 of Fig. 2; and

Fig. 4 is an enlarged fragmentary view of the control mechanism, as seen in Fig. 1.

The reeling mechanism comprises a drum, generally indicated at 10, a cable 11 windable upon the drum, a bar 12 outwardly deflectible in response to the winding of a predetermined critical turn of cable on the drum, and the control mechanism 47, illustrated by Fig. 4, which opens or closes an electrical circuit in response to such outward movement of the bar. The drum comprises a shaft 16 bearing a central winding cylinder 13 between two radial flanges 14 and 15 which may present braking surfaces 48 and 49. Suitable supports 17 and 18 contain bearings 19 and 20 within which shaft 16 is rotatably received. Hoisting power may be applied to the drum through an extension of shaft 16.

45 Bar 12 is of such length as to extend between the flange ends of the drum with limited clearance. The bar contains spaced longitudinal slots 21, through which studs 22 of removable projections or blocks 23, 24 and 25 are receivable. Nuts 26 are applied to the outer ends of the studs to retain the blocks in their respective adjusted positions.

Bar 12 is carried by two spaced upwardly extending arms 27 bearing sleeves 28 which are ro-

ated to permit the bar to be positioned as required.

tatably retained on shaft 29 to permit pivotal movement of the arm and bar assembly as a unit. Shaft 29 is carried for rotation by support bearings 30 which are borne by control base 31.

Two spaced sleeved sectors 32 are carried by shaft 29 adjacent to arms 27, and are suitably retained against rotation relative to the shaft, as by keys 33, see Fig. 2. A bolt 35, retained by a nut 45, extends through each of the arms 27 and an arcuate slot 34 in the adjacent sector 32 to rigidly hold the arm and sector against relative angular movement. When the sectors and arms are thus tightened together, any deflection of bar 12 results in rotation of shaft 29. The arcuate slots permit easy adjustment of the angular relationship between the arms and their adjacent sectors.

Sleeved arm 37, bearing cam 36, is keyed or otherwise secured to shaft 29, to transmit rotation of the shaft into movement of the cam. Upward movement of the cam operates to pivot follower 39 to the left about fulcrum 40 by engagement of roller 38. Such leftward movement of the follower actuates switch 42 through shaft 41 to either open or close the electrical circuit containing leads 43 and 44. The control mechanism is normally urged away from such switch actuating position and toward the position of Figs. 1 and 4 by spring 46.

In operation, drum 10 winds cable 11 uninterruptedly until the condition of Fig. 2 is reached. When the winding is continued beyond that point, the next turn engages the beveled end of projection 25 to commence moving bar 12 outwardly. Such outward deflection rotates shaft 29 by virtue of arms 27 and sectors 32. As the shaft rotates, cam 36 is moved upwardly to pivot follower 39 to the left, and actuate switch 42, which opens or closes a control circuit to stop rotation of the drum or signal the operator, as desired. In addition to this travel limiting operation, the bar is also deflectible in response to fouling of the cable, and the control mechanism is thus operable by such fouling to prevent any accidents which might otherwise result.

The device may be set to react at a desired height of the travelling block by first winding the cable until the block is at that desired height and then setting the two adjustments so that the switch will be actuated by the turn which is being wound at that time. The angular relationship between shaft 29 and the arm and bar assembly is set by the sector adjustments, and the reaction is isolated to the single desired turn by the use of a proper number of correctly positioned blocks.

I claim:

1. A safety device for use with an oil well cable winding drum, comprising a movable member positioned adjacent the drum, means carried by said member and deflectible outwardly from said drum to an operative position removed a predetermined distance therefrom in response to the winding of a predetermined critical turn on said drum, a bolt and slot connection adjustably securing said member and means together to permit varying of the position of said means relative to the drum to thereby determine the turn to which said means will be responsive, and control means responsive to such outward deflection of said means.

2. A safety device for use with an oil well cable winding drum, comprising a bar means for mounting said bar to extend longitudinally of the drum at a position located outwardly therefrom,

said means permitting outward deflection of said bar means carried by said bar to render it deflectible outwardly to an operative position removed a predetermined distance from said drum in response to the winding of a predetermined critical turn on said drum, and control means responsive to such outward deflection of the bar.

3. A safety device for use with an oil well cable winding drum, comprising a bar means for mounting said bar to extend longitudinally of the drum at a position located outwardly therefrom, said means permitting outward deflection of said bar an inwardly facing projection on said bar to engage a predetermined critical turn on said drum and cause outward deflection of the bar to an operative position in which the bar is removed a predetermined distance from said drum in response to the winding of that turn, and control means responsive to such outward deflection of the bar.

4. A safety device for use with an oil well cable winding drum, comprising a bar means for mounting said bar to extend longitudinally of the drum at a position located outwardly therefrom, said means permitting outward deflection of said bar an inwardly facing projection on said bar to engage a predetermined critical turn on said drum and cause outward deflection of the bar to an operative position in which the bar is removed a predetermined distance from said drum in response to the winding of that turn, and control means for varying the position of said projection longitudinally of the bar to permit determination of the particular turn to which the bar will react, and control means responsive to such outward deflection of the bar.

5. A safety device for use with an oil well cable winding drum, comprising a bar means for mounting said bar to extend longitudinally of the drum at a position located outwardly therefrom, said means permitting outward deflection of said bar an inwardly facing projection on said bar to engage a predetermined critical turn on said drum and cause outward deflection of the bar to an operative position in which the bar is removed a predetermined distance from said drum in response to the winding of that turn, said projection comprising a plurality of sections, means for varying the positions of said sections longitudinally of the bar to permit determination of the particular turn to which the bar will react, and control means responsive to such outward deflection of the bar.

6. A safety device for use with an oil well cable winding drum, comprising a bar means for mounting said bar to extend longitudinally of the drum at a position located outwardly therefrom, said means permitting outward deflection of said bar means carried by said bar to render it deflectible outwardly to an operative position removed a predetermined distance from said drum in response to the winding of a predetermined critical turn on said drum, adjustable means for varying the operative position of the bar, and control means responsive to such outward deflection of the bar.

7. A safety device for use with an oil well cable winding drum, comprising a bar means for mounting said bar to extend longitudinally of the drum at a position located outwardly therefrom, said means permitting outward deflection of said bar means carried by said bar to render it deflectible outwardly to an operative position removed a predetermined distance from said drum in response to the winding of a predetermined critical turn on said drum, and control means responsive to such outward deflection of the bar.

mined critical turn on said drum, a pair of pivotally movable arms supporting said bar and permitting the defined outward deflection, and control means responsive to such outward deflection of the bar.

8. A safety device for use with an oil well cable winding drum, comprising an outwardly deflectible member positioned adjacent the side of the drum, means carried by said member and deflectible outwardly from said drum to an operative position removed a predetermined distance therefrom in response to the winding of a predetermined critical turn on said drum, a cam movable in response to movement of said means, and control means actuated by said cam in response to said outward deflection of said means.

9. A safety device for use with an oil well cable winding drum, comprising a bar means for mounting said bar to extend longitudinally of the drum at a position located outwardly therefrom, said means permitting outward deflection of said bar means carried by said bar to render it deflectible outwardly to an operative position removed a predetermined distance from said drum in response to the winding of a predetermined critical turn on said drum, a pair of pivotally movable arms supporting said bar and permitting the defined outward deflection, a cam pivotable with said arms, control means actuated by the pivotal movement of said cam responsive to said outward deflection of the bar, and means for adjusting the angular relationship between said arms and the cam to vary the bar position at which the control means will be actuated.

10. A reeling device for use with oil well hoisting mechanism, comprising a winding drum carrying a cable, a deflectible member, means positioning said member in the path of a predetermined critical turn on said drum to render said member deflectible outwardly to an operative position removed a predetermined distance from said drum in response to the winding of said critical turn, said member presenting an angularly disposed wedge surface engageable by said cable during winding of said critical turn to facilitate said deflection, and control means responsive to such outward deflection of the member.

11. A reeling device for use with oil well hoisting mechanism, comprising a winding drum carrying a cable, an outwardly deflectible bar extending longitudinally of the drum at a position located outwardly therefrom, means rendering

the bar deflectible outwardly to an operative position removed a predetermined distance from said drum in response to the winding of a predetermined critical turn on said drum, and control means responsive to such outward deflection of the bar.

12. A reeling device for use with oil well hoisting mechanism, comprising a winding drum carrying a cable, an outwardly deflectible bar extending longitudinally of the drum at a position located outwardly therefrom, an inwardly facing projection on said bar to engage a predetermined critical turn on said drum and cause outward deflection of the bar to an operative position in which the bar is removed a predetermined distance from said drum in response to the winding of that turn, and control means responsive to such outward deflection of the bar.

13. A reeling device for use with oil well hoisting mechanism, comprising a winding drum carrying a cable, a member extending upwardly from beneath said drum, control means situated beneath said drum and responsive to deflection of said member outwardly from said drum, and means carried by said member to cause such outward deflection of said member in response to the winding of a predetermined critical turn on said drum.

14. A safety device for use with an oil well cable winding drum, comprising a member, means for movably mounting said member in the path of a predetermined critical turn on said drum to render said member deflectible outwardly to an operative position removed a predetermined distance from said drum in response to the winding of said critical turn, said member presenting an angularly disposed wedge surface engageable by said cable during winding of said critical turn to facilitate said deflection, and control means responsive to such outward deflection of the member.
